PROCESS FOR MAKING TETRAMETHYL LEAD

Rudolph L. Pedrotti, Newark, and Charles A. Sandy, Wilmington, Del., assignors to E. I. du Pont de Nemours and Company, Wilmington, Del., a corporation of Delaware
No Drawing. Filed July 5, 1963, Ser. No. 293,138
11 Claims. (Cl. 260—437)

This invention relates to the manufacture of tetramethyl lead, more particularly to its manufacture by the reaction of methyl chloride with monosodium lead alloy in the presence of a novel catalyst system which is highly effective under mild conditions of temperature and pressure.

Recent trends in the formulation of motor gasoline have created a significant demand for tetramethyl lead as an antiknock agent. However, as disclosed in the recent art, for example by Jarvie et al. in U.S. Patent 3,048,610, Tullio in U.S. Patents 3,072,694 and 3,072,695, and Cook et al. in U.S. Patent 3,049,558 the manufacture of tetramethyl lead by the reaction of methyl chloride with sodium lead alloy presents considerable difficulties. In direct contrast to the well-known ethyl chloride-sodium lead alloy system, which does not require catalysis below 100° C. but can be accelerated by ketones, alcohols, esters and other substances known to the art as "ethylation accelerators," the methyl chloride-sodium lead alloy system responds not at all to conditions normally conducive to the formation of tetraethyl lead. In fact, from the disclosures of the recent practitioners of the art, it appears that methylation of sodium lead alloy is unique in that only certain catalysts of the aluminum type have been found to be effective. Such high degree of catalyst specificity appears characteristic also of the mixed methylation-ethylation of sodium lead alloys as disclosed by Calingaert et al. in U.S. Patent 2,270,109.

In general then, it appears from the art that a catalyst effective for ethylation is not necessarily effective for methylation. It is also apparent from the above patents, which are directed particularly and solely to the manufacture of tetramethyl lead, that the aluminum-type catalysts represent the best heretofore known means for effecting reaction of methyl chloride with sodium lead alloy. Such substances are now used in commercial processes for the manufacture of tetramethyl lead. However, they have major drawbacks. They require elevated temperatures at long reaction times, normally temperatures on the order of 100° C. for several hours. Such conditions, in view of the high vapor pressure of methyl chloride, necessitate the use of expensive pressure systems for practical and safe operation. Also, they add to the hazards already inherent in the handling of tetramethyl lead in that they form in the reaction system alkyl aluminum derivatives which are extremely sensitive to air and moisture and tend to ignite spontaneously on exposure to the atmosphere.

It should be noted that the processes of Jarvie et al. and Tullio, though providing for relatively smooth and safe initiation of the aluminum-catalyzed system whereby some of the hazards are alleviated, are not entirely satisfactory in that they still require elevated temperatures for completion of the methylation reaction and do not completely avoid the hazards inherent in handling alkyl aluminum systems.

Thus, the large scale manufacture of tetramethyl lead has continued to present extremely sensitive and serious problems.

It is an object of this invention to provide a new and improved process for the manufacture of tetramethyl lead. Another object is to provide such a process which

is particularly adapted for the large scale manufacture of pure tetramethyl lead. A further object is to effect the reaction of methyl chloride with monosodium lead alloy in an improved manner which mitigates the fire and explosion hazards inherent in the use of the prior art catalyst systems based on aluminum. A particular object is to provide a catalytic process for reacting methyl chloride with monosodium lead alloy wherein the reaction is initiated smoothly and safely at relatively low temperatures and proceeds rapidly and smoothly under relatively mild conditions of temperature and pressure to produce tetramethyl lead in high yields. Other objects are to advance the art. Still other objects will appear hereinafter.

The above and other objects of this invention will be accomplished by the process for making tetramethyl lead which comprises reacting monosodium lead alloy with

(A) A methylating agent which consists essentially of methyl chloride in the liquid phase, employing at least about 1 mole of methyl chloride per mole of alloy,

(B) At a temperature of from about —20° C. to about 120° C.

(C) In the presence of a catalyst system which consists essentially of

(a) From 0.01 to about 1.5 moles of ammonia per mole of alloy,

(b) From 0 to about 0.04 mole of water per mole of alloy, but not more than 0.3% by weight based on the methyl chloride, and

(c) From 0 to 0.04 mole per mole of alloy of a mono-hydroxylic organic compound of the formula ROH wherein R represents a member of the group consisting of hydrocarbon and oxahydrocarbon radicals of 1-18 carbon atoms.

In preferred embodiments, the reaction is effected with about 1.3 to about 3 moles of MeCl, about 0.05 to about 0.6 mole of NH₃, and about 0.00014 to about 0.025 mole of H₂O, provided that the total amount of water does not exceed 0.3% by weight (3000 p.p.m.) of the methyl chloride, and/or about 0.0003 to about 0.025 mole of monohydroxylic organic compound, at temperatures of from about 25° C. to about 85° C. and at pressures of from about 100 to about 300 p.s.i.g. (pounds per square inch gauge). It is particularly preferred to operate at about 35° C. to about 60° C. and about 100 to about 175 p.s.i.g. The abbreviation "p.p.m." means parts per million by weight, i.e. the indicated number of parts per million parts of methyl chloride.

By this process, the methylation is initiated and brought to completion smoothly and rapidly under mild conditions. In general, temperatures can be lower and reaction times shorter, while the yields of tetramethyl lead are as high or higher than in the recently patented processes of Jarvie et al., Tullio and Cook et al., involving aluminum-based catalyst systems. Moreover, the catalyst systems of this invention avoid the hazards involved in handling and processing the aluminum catalysts and the reaction masses produced therefrom. Thus, the manufacture of tetramethyl lead is made significantly more safe, practical and economic.

The presence of ammonia in the catalyst system is critical. Without it, practically no tetramethyl lead is produced. Broadly, the quantity of ammonia will correspond to 0.01 to about 1.5 moles per mole of alloy, the actual amount depending on such factors as the amount of methyl chloride used, the temperature and time of reaction and the nature and proportion of the co-catalyst components. More usually, the molar ratio of ammonia to alloy ranges from about 0.05 to about 0.6. In general, the lower the ammonia to alloy ratio the higher the specificity of the reaction, that is, the

higher the ratio of the conversion of alloy to tetramethyl lead to the total conversion of alloy to all products, less alloy being consumed in side reactions to produce other products. On the other hand, sufficient ammonia is normally needed to provide reasonable rates of tetramethyl lead formation. The reaction variables are easily coordinated to produce tetramethyl lead radibly in high yields under extremely mild conditions of temperature and pressure. For example, particularly good results are obtained in the preferred embodiments with ammonia to alloy molar ratios in the range of about 0.05 to about 0.3 at temperatures of from about 25° C. to about 85° C.

It has also been discovered that water or a monohydroxylic organic compound in controlled proportions as defined can exert a marked co-catalytic effect to increase the rate of the ammonia-catalyzed methylation reaction and/or the specificity of that reaction. Thus, in contrast to prior practice regarding the alkylation of monosodium lead alloy, it is not critical for practical operation to exclude or limit moisture to very low levels. This has a commercially important advantage because the methyl chloride ordinarily contains small amounts of water and it is not economically practical to provide completely anhydrous methyl chloride. Methyl chloride, containing 50 p.p.m. or less of water, is generally considered in this art to be substantially anhydrous. For example, in the methylation reaction involving aluminum-type catalysts, it is normally considered desirable to limit the water content of the methyl chloride to less than about 150 p.p.m. water (0.015% wt.) and in general to operate as anhydrously as possible. Substantially larger water levels may, if desired, be present in the methyl chloride according to the present invention, for example on the order of 500 to 3000 p.p.m., 0.05% to 0.3% by weight, provided of course the total water introduced into the reaction mixture does not amount to more than about 0.04 mole per mole of alloy and does not exceed about 0.3% by weight of the MeCl . The presence of gross water tends to depress the yields of tetramethyl lead markedly. Preferred water to alloy ratios are in the range 0.00014–0.025 mole. Based on MeCl , the preferred range is about 50 to about 3000 p.p.m., about 0.005% to about 0.3% by weight, particularly about 100 to about 1000 p.p.m., about 0.01% to about 0.1% by weight.

There may also be used as defined, in conjunction with said water, or alone as the sole ammonia activator, one or more monohydroxylic organic compounds composed of carbon, hydrogen and one or more oxygens, and containing up to 18 carbon atoms, and no oxygens other than ether and hydroxyl oxygens. In other words, the hydroxylic component need only contain one hydroxyl group and be otherwise essentially inert as far as the alloy is concerned, that is, contain only hydrocarbon and oxahydrocarbon radicals. Also, the monohydroxylic organic compound can be defined as a compound of the formula ROH wherein R is a hydrocarbon or an oxahydrocarbon radical of 1–18 carbon atoms, said oxa designation standing for ether oxygen. Thus, there may be used a variety of aliphatic and cycloaliphatic alcohols consisting of, in addition to said OH group, hydrocarbon or etherhydrocarbon radicals. Similarly, there may be used phenol and phenols containing hydrocarbon and etherhydrocarbon substituents. The activating effect appears to be specific to the monohydroxylic compounds, corresponding polyhydroxylic compounds appearing to have little or no activating or promoting effect.

Representative monohydroxylic organic compounds are the simple alkanols and cycloalkanols such as methanol, ethanol, 1- and 2-propanol, 1-butanol, 2-methyl-2-propanol, pentanol, hexanol, 3,5,5-trimethylhexanol, cyclopentanol and cyclohexanol; naturally-occurring fatty alcohols such as the mixtures derived from coconut oil for example and including decanol, dodecanol (lauryl alcohol), tetradecanol (myristyl alcohol), hexadecanol (cetyl alcohol) and octadecanol (stearyl alcohol); alcohols made

by the Oxo process such as oxo-octyl alcohol and oxotridecanol; unsaturated alcohols such as allyl alcohol, oleyl alcohol and propargyl alcohol; ether alcohols such as ethylene glycol monomethyl ether (methyl cellosolve), ethylene glycol monoethyl ether, ethylene glycol monobutyl ether, and diethylene glycol monomethyl ether; phenolics such as phenol, o-, m- and p-cresol, the xylenes, p-nonyl phenol, and resorcinol monomethyl ether. Mixtures of any two or more of the monohydroxylic organic compounds may be used.

Methanol or other lower alkanol (of 1–4 carbon atoms) is highly preferred for it is particularly effective as an activator for the ammonia component both to accelerate the methylation reaction and to favor the formation of tetramethyl lead at the expense of side reaction such as those leading to volatile hydrocarbons.

Such monohydroxylic component may be present in molar proportions as high as about 0.04 mole per mole of alloy, preferably from about 0.0003 to about 0.025 mole per mole of alloy. Also preferably and more usually, the combined (total) amount of water and monohydroxylic organic compound will not exceed about 0.04 mole per mole of alloy.

The term methyl halide methylating agent consisting essentially of methyl chloride includes methyl chloride as the essential source of methyl groups and mixtures thereof with up to about 5 mole percent of methyl iodide based on the methyl chloride, more usually less than about 1 mole percent of said methyl iodide. Such small proportions of such methyl iodide, e.g. 0.1–1 mole percent may have beneficial effects. For example, methyl iodide appears effective at low temperatures in conjunction with said ammonia catalyst to accelerate the methylation reaction and thereby increase the rate of production of tetramethyl lead. While the iodide may be present in small proportions as above, the ammonia catalyzed process appears unique for methyl chloride as the essential methylating agent.

The methylating agent is normally employed in amounts of at least about one mole and usually not more than about 5 moles per mole of alloy. Larger quantities, up to 20 moles, may be used but are not necessary. Preferred ratios are in the range of about 1.3 to about 3 moles of methyl chloride per mole of alloy.

The monosodium lead alloy (NaPb) to be used in this process, i.e. containing 50 mole percent Na and 50 mole percent Pb, or on a weight basis 10% wt. Na and 90% wt. Pb, has been amply described in the art. It may be used in various forms, usually comminuted, including ground as disclosed by Stecher in U.S. Patent 2,134,091, flaked as disclosed by Pyk in U.S. Patent 2,561,636 or by Tanner in U.S. Patent 2,635,107, and quenched (in MeCl) as described by Mattison in U.S. Patent 2,744,126.

Broadly, the overall process comprises (1) mixing the alloy, methyl halide, ammonia and, when desired, water or other monohydroxylic co-catalyst component, (2) holding such mixture at a temperature in the range of -20°C . to about 120°C . at which the reaction is initiated and proceeds at a reasonable rate, and (3) recovering the tetramethyl lead from the reaction mass. Normally, the reaction is effected under agitation and it is usually desirable to effect the reaction in the presence of an inert solid, such as graphite, as an internal lubricant. From about 1% to about 5% by weight of graphite based on the alloy may be used, depending on the dimensions of the reactor, the effectiveness of the agitation means, and the proportions of the reactants. There may also be present, a thermal stabilizer for tetramethyl lead, as described in the art by Jarvie et al. in U.S. Patent 3,048,610 and Cook et al. in U.S. Patent 3,049,558, for example a volatile hydrocarbon such as toluene or isoctane having boiling characteristics comparable to those of tetramethyl lead.

The reactants, catalyst components and other agents

(as described above) may be introduced separately or together, all at once or gradually during the course of the reaction. The ammonia and the co-catalyst components may be added as such or in a carrier which conveniently may be the methylating agent or an inert solvent including the thermal stabilizers toluene and isoctane. Ammonia, normally gaseous like methyl chloride, may be charged to the reactor as condensed liquid or as pressurized vapor.

The reaction mass components may be mixed at low temperatures at which the reaction does not proceed at a substantial rate, e.g. at -70° C . or below, and the mixture then brought to operating temperatures. Or the reactants and other essential components may be brought into contact at temperatures within the operating range, preferably in the preferred 25° C . to 85° C . range. The reaction may be conducted batchwise or continuously.

An important feature of this invention is that the ammonia-catalyst system effects the methylation reaction at low temperatures and low pressures. Reaction mass temperatures are readily controlled by controlling the amount and schedule of catalyst and methyl chloride addition, by cooling where necessary and by refluxing methyl chloride, to keep the internal pressure at desired levels, sufficient to maintain the methyl chloride in liquid phase or under reflux pressure, for example below 300 p.s.i.g. Indeed, at temperatures of from 25° C . to 85° C ., pressures are easily maintained in the 100-300 p.s.i.g. region. Of

values of Y/C , times 100, being the percent alloy consumed in side reactions.

The following examples are given to more fully illustrate the invention, preferred modes of operation, and the advantageous results to be obtained thereby. The quantities are in parts by weight unless otherwise noted.

Example 1

The data, shown in Table I below, were obtained according to the following procedure, involving a stainless steel pressure reactor equipped with outer electrical heating means and inner thermocouples for measuring temperature, and adapted for agitation by shaking. The reactor volume is such that 100 parts MeCl corresponds to a loading density of 0.25 gr./cc.

One hundred parts crushed NaPb and 4.3 parts toluene were added to the reactor under nitrogen. The reactor was then closed, cooled to -70° C . and evacuated. Then, in turn, ammonia, to provide concentrations as tabulated below, and 69 parts of methyl chloride, containing 60 p.p.m. H_2O , were weighed in from pressurized supplies. Agitation was started and the reaction mixture brought to reaction temperature in 5 to 10 minutes and held there for the time periods indicated below. Reaction was terminated by cooling to -70° C . Tetramethyl lead was recovered by extracting the reaction product with toluene.

Typical results, obtained under various conditions of temperature, ammonia concentration, and reaction time are shown in Table I.

TABLE I.—AMMONIA CATALYZED MeCl-NaPb REACTION
[Molar MeCl/NaPb = 3.1; molar $\text{H}_2\text{O}/\text{NaPb} = 0.0005$]

Run	Temp., $^{\circ}\text{ C}$.	Time, Hours	NH ₃ Concentration		Y, Percent	C, Percent	Y/C
			Percent Wt. Alloy	Mole/Mole NaPb

5	*-20 to -70	0.75	2	0.27	29	86	.34

*The temperature was raised from -70° C . to -20° C . during 45 minutes from the time the methyl chloride was introduced; and the reaction mixture was agitated only for the middle third of the 45 minutes period.

course, higher pressures may be used, e.g. 1000 p.s.i.g., but are rendered unnecessary by the use of ammonia in accordance with this invention. The importance of these results is that a greater degree of safety is achieved and at lower operating cost, considering the hazards and expense involved in having a relatively unstable product, such as tetramethyl lead, confined at elevated temperatures.

The resulting reaction mass may be worked up in the usual ways described in the art. Normally, the residual methyl chloride is vented from the charge at a temperature in the range of about 25° C . to about 60° C ., and passed to a recovery system as in tetraethyl lead technology. For this purpose, the temperature of the reaction mixture is adjusted accordingly, if necessary. The tetramethyl lead product is then recovered by solvent extraction, e.g. with toluene, or by steam distillation according to the well-known techniques.

In the examples, Y, percent is the percent of the theoretical yield of tetramethyl lead based on the quantity of alloy employed; C, percent is the total percent of the alloy consumed by reaction to produce tetramethyl lead and other products, and Y/C is the ratio of the percent yield of tetramethyl lead (and of the percent of the alloy that is consumed in producing tetramethyl lead) to the total percent alloy consumed in all reactions. Thus, Y/C is a measure of the reaction specificity to produce tetramethyl lead, the difference between 1.00 and the given

50 The data show that, while the process is broadly operable over a wide range of conditions, the use of relatively low NH₃ concentrations and moderate temperatures provides better overall results in terms yield (Y) and efficiency (Y/C).

Example 2

55 The following test procedure was employed to further illustrate the method of the invention and the advantageous results to be obtained thereby under mild conditions.

60 A steel bomb was charged with 100 parts of crushed monosodium lead alloy enclosed in a glass ampoule. Then with the bomb cooled at the temperature of solid carbon dioxide (-70° C .), there were added under nitrogen 87.5 parts (4 moles/mole alloy) of methyl chloride, containing small quantities of water as tabulated below, and weighed quantities of other additives, also as indicated below. In this system the bomb volume is such that the loading density of MeCl to bomb space is 0.35 gram/cc. The bomb was closed, immersed in a heating bath to bring the contents to reaction temperatures and the ampoule of alloy broken by striking the bomb against a solid object. The bomb was shaken vigorously at reaction temperature for a given reaction period, then the reaction was terminated as in Example 1, the bomb opened and the reaction mixture analyzed for alloy consumption and 65 yield of tetramethyl lead.

Results obtained with a series of such bomb runs are shown in Tables II, III and IV.

TABLE II.—AMMONIA CATALYZED MeCl-NaPb REACTION EFFECT OF AMMONIA CONCENTRATION
[60 p.p.m. H_2O in the MeCl ; molar $\text{H}_2\text{O/NaPb} = 0.00067$; reaction temp. = 25°C , time = 0.5 hour]

Run	NH ₃ Concentration		Y, Percent	C, Percent	Y/C

9	0.1	0.014	5	-----	-----
10	0.0	0.0	nil	-----	-----

It will be noted that Runs 6 and 10 of Table II are not of this invention. They show that the NH₃ component is necessary but that excessive proportions result in a highly inefficient reaction system as shown by the low Y/C ratio in Run 6. Furthermore, in Run 6, about

150 p.p.m. H_2O was used in place of methyl chloride, with ammonia concentration between 0.5 and 2 wt. percent of the alloy and temperatures in the 25°C . to 50°C . range, tetraethyl lead was obtained in yields of less than 1%.

TABLE IV.—AMMONIA CATALYZED MeCl-NaPb REACTION EFFECT OF ORGANIC HYDROXYLIC ADDITIVE

¹ Less than 1%.

75% of the methyl chloride charged to the reactor was consumed in side reactions (apparently in reactions with ammonia). In contrast, under these conditions but with the smaller proportions of ammonia characterizing this invention, methyl chloride losses in side reactions are materially less. With preferred NH₃ concentrations of 2 parts or less by weight per 100 parts alloy, methyl chloride losses are practically negligible and substantially all the excess methyl chloride charged can be recovered.

TABLE III.—AMMONIA CATALYZED MeCl-NaPb REACTION EFFECT OF TEMP. AND WATER CONCENTRATION
[Molar NH₃/NaPb = 0.068; reaction time = 0.5 hour]

Run	Temp., $^\circ\text{C}$.	H ₂ O Concentration		Y, percent	C, percent	Y/C
		p.p.m. on MeCl	Mole/Mole NaPb

17	50	220	0.0027	95	97	.98

¹ 75 parts (3.42 moles/mole NaPb) methyl chloride.

Run 15, involving a rather large proportion of H₂O (corresponding to 6.7% wt. based on MeCl and 63 mole percent based on alloy), is outside the scope of this invention. Also, in Runs 13 and 14, the water is in excess of 0.3% by weight based on the methyl chloride. Runs 13-15 show, in comparison with Run 8 of Table II and Runs 11-12 above, that the proportion of water in the catalyst system is important for operability and for achieving optimum results.

70 hydroxylic organic compound, while essentially inoperative alone for promoting methylation, exerts the beneficial effect, in controlled amounts, of increasing alloy reaction rate (increased conversion C in a given time as shown) and of enhancing the yield Y and usually also the specificity of the reaction (Y/C).

Example 3

Run 8 of Table II, Example 2 was repeated with a 75 charge consisting of 87.5 parts MeCl containing 50 p.p.m.

H_2O , 1.4 parts MeI , 0.5 parts NH_3 and 100 parts $NaPb$. This corresponds to 4 moles $MeCl$, 0.068 mole NH_3 and 0.00056 mole H_2O per mole of alloy, and 0.6 mole percent of MeI based on the $MeCl$. The yield of tetramethyl lead was 63% with $Y/C=0.91$. Comparison with Run 8 (44% yield of tetramethyl lead with $Y/C=0.90$) shows that the small proportion of methyl iodide under these conditions has the beneficial effect of accelerating the methylation reaction.

Example 4

A 5-gallon alkylation autoclave (equipped with agitator, temperature and pressure sensing and control means, and inlet and outlet means for the addition and removal of reactants) was charged with 35 lbs. of crushed monosodium lead alloy, 1.4 lbs. of toluene and 0.4 lb. of flaked graphite. Agitation was started and the internal temperature adjusted to 25° C.-30° C. To start, one lb. of methyl chloride and 0.088 lb. of ammonia were pressurized into the system to provide a pressure about 60 p.s.i.g. Then, continuous feeding was begun simultaneously of additional methyl chloride at the rate of about 0.1 lb./minute and of additional ammonia at the rate of about 0.0022 lb./minute. Feeding of both the methyl chloride and ammonia was terminated after about 2 hours, at the end of which time a total of 10 lbs. of methyl chloride (1.3 moles/mole alloy) and 0.44 lb. of ammonia had been introduced, and during which time also the reaction temperature had been allowed to rise to a maximum of 50° C. and the pressure reached a maximum of 120 p.s.i.g. The reaction mixture was held for 0.5 hour longer under agitation at 40° C.-50° C. and about 110-120 p.s.i.g, vented and cooled to about 25° C., discharged to a steam still and steam-distilled to obtain 7.9 lbs. of tetramethyl lead corresponding to a yield of 78% based on the alloy.

The methyl chloride used in this run contained 40 p.p.m. water (0.004 wt. percent) whereby the molar ratio of total water introduced to alloy is 0.00014. Such conditions may be regarded as substantially water-free inasmuch as this same methyl chloride is suitable for use in the otherwise essentially anhydrous aluminum-catalyzed processes of Jarvie et al., in U.S. Patent 3,048,610 and Tullio in U.S. Patents 3,072,694-5. The molar ratio of ammonia to alloy in the above run is 0.17, whereby it is apparent that ammonia is highly effective in small amounts as a low-temperature, low-pressure, high-production rate catalyst for the $MeCl-NaPb$ system.

Example 5

The procedure of Example 4, involving slow feed of both methyl chloride and ammonia, was repeated in the same equipment with the same reagents and under substantially the same conditions except that (a) there was employed a smaller total charge consisting of 18 lbs. $NaPb$ alloy, 6.3 lbs. $MeCl$ containing 40 p.p.m. H_2O , and 0.26 lb. NH_3 , corresponding to about 1.6 moles $MeCl$, about 0.00018 mole H_2O , and about 0.2 mole NH_3 per mole of alloy; (b) the reaction temperature was maintained at a maximum of 38° C., and the pressure at a maximum of 100 p.s.i.g., and (c) the total reaction time was 2 hours. The yield of tetramethyl lead was 83% of theoretical based on the alloy.

Example 6

In the reactor of Example 4, were charged 35 lbs. of crushed $NaPb$, 1.4 lbs. toluene, 0.4 lb. graphite and 12 lbs. $MeCl$ (1.56 moles/mole $NaPb$) at a pressure of about 100 p.s.i.g. The resulting mixture was warmed to 35° C. under agitation and treated with 0.11 lb. of a catalyst mixture consisting of 6.4 wt. percent methanol and 93.6 wt. percent ammonia. Following this initial increment, an additional 0.28 lb. of the catalyst mixture was fed during 1.5 hours at such a rate (about 0.002-0.004 lb./minute) that the reaction mass temperature did not exceed about 40° C. and the pressure about 115 p.s.i.g. The reaction

mass was held at 35°-40° C. for 0.25 hours before being worked up as described in Example 3 to yield 9.5 lbs. of tetramethyl lead, 93.7% of theoretical.

In this run, the molar ratios of the total amount of NH_3 , H_2O (40 p.p.m. in the $MeCl$), and CH_3OH to alloy were 0.14, 0.00017 and 0.0058, respectively.

On repeating this procedure substantially as described above except that the methylation is effected at 60° C. and 175 p.s.i.g. for a total reaction time of 1.33 hours, tetramethyl lead is produced in 91% yield.

Substantially the same yield (about 90%) was obtained at 60° C.-65° C. (175-180 p.s.i.g.) with a smaller proportion of $MeOH$, 0.018% by weight of the alloy, 0.0013 mole/mole $NaPb$.

When methanol is omitted and the conditions of the above example are otherwise substantially the same, i.e. at 60° C., the tetramethyl lead yields are 80-83%, whereby it is apparent that methanol used according to this invention exerts a marked beneficial effect on the ammonia-catalyzed process.

It will be understood that the foregoing examples are given for illustrative purposes solely and that this invention is not limited to the specific embodiments described therein. On the other hand, it will be apparent to those skilled in the art that, subject to the limitations set forth in the general description, many variations can be made in the materials, proportions, conditions and techniques employed without departing from the spirit or scope of this invention.

From the foregoing description, it will be apparent that this invention provides a new and improved process for making tetramethyl lead employing a novel catalyst system. The use of such catalyst system makes it possible to efficiently manufacture tetramethyl lead in high yields and high purity under milder conditions than were possible heretofore and with a much greater degree of safety. Also, the process requires only short reaction times, resulting in greater capacity of the equipment. Particularly, the process of this invention results in important economic advantages. Accordingly, this invention constitutes a valuable advance in and contribution to the art.

The embodiments of the invention in which an exclusive property or privilege is claimed are defined as follows:

1. The process for making tetramethyl lead which comprises reacting monosodium lead alloy with

- (A) a methylating agent which consists essentially of methyl chloride in the liquid phase, employing at least about 1 mole of methyl chloride per mole of alloy,
- (B) at a temperature of from about -20° C. to about 120° C.
- (C) in the presence of a catalyst system which consists essentially of
  - (a) from 0.01 to about 1.5 moles of ammonia per mole of alloy and
  - (b) up to about 0.04 mole of water per mole of alloy, but not more than 0.3% by weight based on the methyl chloride,
- (D) the total amount of water present not exceeding that specified in (b) above.

2. The process for making tetramethyl lead which comprises reacting monosodium lead alloy with

- (A) a methylating agent which consists essentially of methyl chloride in the liquid phase, employing from about 1.3 to about 4 moles of methyl chloride per mole of alloy,
- (B) at a temperature of from about 25° C. to about 85° C.
- (C) in the presence of a catalyst system which consists essentially of
  - (a) from about 0.05 to about 0.6 mole of ammonia per mole of alloy and
  - (b) from about 0.00014 to about 0.025 mole of water per mole of alloy, but not more than 0.3% by weight based on the methyl chloride,

- (D) the total amount of water present not exceeding that specified in (b) above.
3. The process for making tetramethyl lead which comprises reacting monosodium lead alloy with
- (A) a methylating agent which consists essentially of methyl chloride in the liquid phase, employing from about 1.3 to about 4 moles of methyl chloride per mole of alloy, 5
- (B) at a temperature of from about 35° C. to about 60° C.
- (C) in the presence of a catalyst system which consists essentially of
- (a) from 0.05 to about 0.3 mole of ammonia per mole of alloy and
- (b) from about 0.00014 to about 0.025 mole of 15 water per mole of alloy, but not more than 0.3% by weight based on the methyl chloride,
- (D) the total amount of water present not exceeding that specified in (b) above.
4. The process for making tetramethyl lead which comprises reacting monosodium lead alloy with 20
- (A) a methylating agent which consists essentially of methyl chloride in the liquid phase, employing at least about 1 mole of methyl chloride per mole of alloy,
- (B) at a temperature of from about -20° C. to about 25° C.
- (C) in the presence of a catalyst system which consists essentially of
- (a) from 0.01 to about 1.5 moles of ammonia per mole of alloy,
- (b) up to about 0.04 mole of water per mole of alloy, but not more than 0.3% by weight based on the methyl chloride, and
- (c) up to about 0.04 mole per mole of alloy of a 35 monohydroxylic organic compound of the formula ROH wherein R represents a member of the group consisting of hydrocarbon and oxahydrocarbon radicals of 1-18 carbon atoms,
- (D) the total amount of water present not exceeding 40 that specified in (b) above.
5. The process for making tetramethyl lead which comprises reacting monosodium lead alloy with
- (A) a methylating agent which consists essentially of methyl chloride in the liquid phase, employing from about 1.3 to about 4 moles of methyl chloride per mole of alloy, 45
- (B) at a temperature of from about 25° C. to about 85° C.
- (C) in the presence of a catalyst system which consists essentially of
- (a) from about 0.05 to about 0.6 mole of ammonia per mole of alloy,
- (b) from about 0.00014 to about 0.025 mole of 55 water per mole of alloy, but not more than 0.3% by weight based on the methyl chloride, and
- (c) from about 0.0003 to about 0.025 mole per mole of alloy of a monohydroxylic organic compound of the formula ROH wherein R represents a member of the group consisting of hydrocarbon and oxahydrocarbon radicals of 1-18 carbon atoms,
- (D) the total amount of water present not exceeding 60 that specified in (b) above.
6. The process for making tetramethyl lead which comprises reacting monosodium lead alloy with
- (A) a methylating agent which consists essentially of methyl chloride in the liquid phase, employing at least about 1 mole of methyl chloride per mole of alloy, 65
- (B) at a temperature of from about -20° C. to about 120° C.
- (C) in the presence of a catalyst system which consists essentially of

- (a) from 0.01 to about 1.5 moles of ammonia per mole of alloy,
- (b) up to about 0.04 mole of water per mole of alloy, but not more than 0.3% by weight based on the methyl chloride, and
- (c) up to about 0.04 mole of methanol per mole of alloy,
- (D) the total amount of water present not exceeding that specified in (b) above.
7. The process for making tetramethyl lead which comprises reacting monosodium lead alloy with
- (A) a methylating agent which consists essentially of methyl chloride in the liquid phase, employing from about 1.3 to about 4 moles of methyl chloride per mole of alloy,
- (B) at a temperature of from about 25° C. to about 85° C.
- (C) in the presence of a catalyst system which consists essentially of
- (a) from about 0.05 to about 0.6 mole of ammonia per mole of alloy,
- (b) from about 0.00014 to about 0.025 mole of water per mole of alloy, but not more than 0.3% by weight based on the methyl chloride, and
- (c) from about 0.0003 to about 0.025 mole of methanol per mole of alloy,
- (D) the total amount of water present not exceeding that specified in (b) above.
8. The process for making tetramethyl lead which comprises reacting monosodium lead alloy with
- (A) a methylating agent which consists essentially of methyl chloride in the liquid phase, employing from about 1.3 to about 3 moles of methyl chloride per mole of alloy,
- (B) at a temperature of from about 35° C. to about 60° C.
- (C) in the presence of a catalyst system which consists essentially of
- (a) from about 0.05 to about 0.3 mole of ammonia per mole of alloy,
- (b) from about 0.00014 to about 0.003 mole of water per mole of alloy, but not more than 0.3% by weight based on the methyl chloride, and
- (c) from about 0.0003 to about 0.025 mole of methanol per mole of alloy,
- (D) the total amount of water present not exceeding that specified in (b) above.
9. The process for making tetramethyl lead which comprises reacting monosodium lead alloy with
- (A) a methylating agent which consists essentially of methyl chloride in the liquid phase, employing at least about 1 mole of methyl chloride per mole of alloy,
- (B) at a temperature of from about -20° C. to about 120° C.
- (C) in the presence of a catalyst system which consists essentially of
- (a) from 0.01 to about 1.5 moles of ammonia per mole of alloy,
- (b) from 0 to about 0.04 mole of water per mole of alloy, but not more than 0.3% by weight based on the methyl chloride, and
- (c) from 0 to about 0.4 mole per mole of alloy of a monohydroxylic organic compound of the formula ROH wherein R represents a member of the group consisting of hydrocarbon and oxahydrocarbon radicals of 1-18 carbon atoms,
- (D) the total amount of water present not exceeding that specified in (b) above.
10. The process for making tetramethyl lead which comprises reacting monosodium lead alloy with
- (A) a methylating agent which consists essentially of methyl chloride in the liquid phase, employing from about 1.3 to about 4 moles of methyl chloride per mole of alloy,

13

- (B) at a temperature of from about 25° C. to about 85° C.
- (C) in the presence of a catalyst system which consists essentially of
- (a) from about 0.05 to about 0.6 mole of ammonia per mole of alloy,
  - (b) from 0 to about 0.04 mole of water per mole of alloy, but not more than 0.3% by weight based on the methyl chloride, and
  - (c) from 0 to about 0.4 mole per mole of alloy of a monohydroxylic organic compound of the formula ROH wherein R represents a member of the group consisting of hydrocarbon and oxa-hydrocarbon radicals of 1-18 carbon atoms,
- (D) the total amount of water present not exceeding 15 that specified in (b) above.
11. The process for making tetramethyl lead which comprises reacting monosodium lead alloy with
- (A) a methylating agent which consists essentially of methyl chloride in the liquid phase, employing from 20 about 1.3 to about 4 moles of methyl chloride per mole of alloy,
  - (B) at a temperature of from about 35° C. to about 60° C.

14

- (C) in the presence of a catalyst system which consists essentially of
- (a) from 0.05 to about 0.3 mole of ammonia per mole of alloy,
  - (b) from 0 to about 0.04 mole of water per mole of alloy, but not more than 0.3% by weight based on the methyl chloride, and
  - (c) from 0 to about 0.04 mole per mole of alloy of a monohydroxylic organic compound of the formula ROH wherein R represents a member of the group consisting of hydrocarbon and oxa-hydrocarbon radicals of 1-18 carbon atoms,
- (D) the total amount of water present not exceeding that specified in (b) above.

UNITED STATES PATENT OFFICE
CERTIFICATE OF CORRECTION

Patent No. 3,281,442

October 25, 1966

Rudolph L. Pedrotti et al.

It is hereby certified that error appears in the above numbered patent requiring correction and that the said Letters Patent should read as corrected below.

Column 1, line 48, for "The" read -- They --; line 63, for "require elevated" read -- require rather elevated --; column 2, line 30, for "to 0.04" read -- to about 0.04 --; column 3, line 7, for "radidly" read -- rapidly --; line 16, for "ammonia-catalpzed" read -- ammonia-catalyzed --; line 75, for "(cetyl alcohol and" read -- (cetyl alcohol) and --; column 8, line 18, for "Concentration" read -- Concentrations --; column 13, line 10, for "0.4" read -- 0.04 --.

Signed and sealed this 5th day of September 1967.
